UNITED STATES PATENT OFFICE.

JESSIE D. DENSON, OF GRAND RAPIDS, MICHIGAN.

LANDING-BRAKE FOR AEROPLANES.

1,360,901.

Specification of Letters Patent. Patented Nov. 30, 1920.

Application filed July 8, 1920. Serial No. 394,739.

To all whom it may concern:

Be it known that I, JESSIE D. DENSON, a citizen of the United States, residing at Grand Rapids, in the county of Kent, State 5 of Michigan, have invented certain new and useful Improvements in Landing-Brakes for Aeroplanes; and I do hereby declare the following to be a full, clear, and exact description of the invention, such as will enable others skilled in the art to which it 10 pertains to make and use the same.

This invention relates to new and useful improvements in aeroplanes and particularly to landing means therefor.

15 The principal object of the invention is to provide a novel and improved attachment for an aeroplane by means of which the speed in landing can be greatly checked, and the usual long glide along the ground, 20 after landing, obviated.

Another object is to provide a novel and improved attachment for an aeroplane of the monoplane type whereby the aeroplane can be gotten off the ground in less time 25 than heretofore.

Other objects and advantages will be apparent from the following description when taken in connection with the accompanying drawing.

30 In the drawing:

Figure 1 is a front elevation of an aeroplane of the monoplane type showing the invention applied thereto.

Fig. 2 is a side elevation of the same, the 35 landing planes being in position to check the landing speed of the aeroplane.

Fig. 3 is a bottom plan view of the same.

Referring particularly to the accompanying drawing, 10 represents the fuselage of 40 the aeroplane to which are secured the sustaining planes 11, the aeroplane being of the monoplane type. In each side of the forward portion of the fuselage there is formed a longitudinally extending slot 12, and disposed through the slots, transversely of the fuselage, and with its ends projecting beyond both sides of the fuselage, is a shaft 13. Mounted transversely of the fuselage, rearwardly of the shaft 13, is a crank shaft 50 14, the ends of which project beyond the opposite sides of the fuselage. Horizontal, outwardly extending planes 15 are centrally pivoted on the projecting ends of the shaft 13, and in the rear ends of the said planes

the ends of the crank shaft 14 are engaged 55 for rocking movement.

Pivots connected to the lower sides of the sustaining planes are the brace arms 16, the lower ends of which are pivotally connected to the ends of the shaft 13. 60

Mounted in the fuselage is a controlling lever 17 which is connected by a link 18 to the crank portion of the shaft 14, whereby, upon movement of the lever the shaft may be rocked and the landing planes 15 moved 65 upwardly and forwardly, or downwardly and rearwardly.

Thus when the aeroplane is flying in the air, at an elevation, or near the ground, as in making a landing, the planes 15 are 70 shifted and tilted downwardly and rearwardly, with the result that the air will strike the under faces thereof and cause the rear end of the aeroplane to rise and the forward end to be depressed, with the result 75 that landing speed will be checked to such a point that the usual long runs, after reaching the ground, are reduced to a minimum.

What is claimed is:

1. The combination with the fuselage and sustaining plane of an aeroplane, the former having longitudinal slots in its opposite sides, of a transverse shaft disposed through the slots, a crank shaft mounted transversely of the fuselage, landing planes pivotally mounted centrally on the transverse shaft and pivotally connected to the crank shaft, and means for rocking the crank shaft to rock the landing planes. 80 85 90

2. The combination with the fuselage and sustaining plane of an aeroplane, the former having longitudinal slots in its sides, of a shaft disposed for slidable movement longitudinally of the slots and rockable therein, 95 speed checking planes mounted on the ends of the shaft for rocking movement thereon and slidable movement therewith, a crank shaft for accomplishing the rocking and sliding movement of the shaft, and braces 100 connected to the ends of the rock shaft and with the sustaining plane.

In testimony whereof, I affix my signature, in the presence of two witnesses.

JESSIE D. DENSON.

Witnesses:

FAY W. EBBO,
WM. GELDERSMA.
